UNITED STATES PATENT OFFICE.

HENRY J. GAISMAN, OF NEW YORK, N. Y.

SUSPENDER-BUCKLE.

SPECIFICATION forming part of Letters Patent No. 793,367, dated June 27, 1905.

Application filed April 9, 1904. Serial No. 202,330.

To all whom it may concern:

Be it known that I, HENRY J. GAISMAN, a citizen of the United States, residing in New York city, borough of Manhattan, New York, have invented certain new and useful Improvements in Suspender-Buckles, of which the following is a specification.

My invention relates to improvements in devices for adjusting the length of the shoulder straps or webs in suspenders and similar articles, and has for its object to provide means to permit the ready manipulation of the movable gripping member or lever of the buckle and to cover the same to prevent it from wearing the lining of vests and the like and from corroding or rusting from perspiration.

My invention comprises the novel details of improvement that will be more fully herein-after set forth and then pointed out in the claims.

Reference is to be had to the accompanying drawings, forming part hereof, wherein—

Figure 1 is a face view of a portion of a pair of suspenders embodying my invention. Fig. 2 is a sectional view, enlarged, on the line 2 2 in Fig. 1. Fig. 3 is an enlarged detail view of my improvements, showing the gripping member thrown upwardly out of action. Fig. 4 is a similar view showing the details of construction of the gripping member; and Fig. 5 is a detail perspective view, enlarged, of the gripping member and its support.

Similar numerals of reference indicate corresponding parts in the several views.

The numeral 1 indicates the shoulder strap or web of a pair of suspenders of the kind adapted to be folded, as at 1^a, to support the suspender-ends 2 and provided with a frame 3, connected with the free end of the web or strap 1 in usual manner. (See Fig. 2.)

At 4 is indicated the movable gripping member or lever of the buckle, which is provided with one or more teeth 4^a to grip the web or strap and hinged upon the frame 3, as by eyes 4^b, (see Fig. 5,) the web 1 passing between frame 3 and the member or lever 4. At 4^c the member or lever 4 has an extension, and said member or lever is inclosed within a covering or shield 5, of flexible smooth material, such as leather or fabric. As shown, the cover-

ing or shield 5 is folded around the member or lever 4, so as to inclose the same, and is provided with an extended flexible tab-like portion 5^a, that projects beyond the extension 4^c to permit ready manipulation of the lever. After 55 the covering or shield 5 is looped around the member or lever 4 to inclose the latter, the portions 5^b 5^c of said cover are secured together, as by stitches 6, to confine the member or lever 4 within such cover, and the teeth 60 4^a may pass through the cover, so as to grip web 1, slots 5^d being provided in the cover for that purpose. (See Fig. 4.)

The arrangement is such that the gripping member or lever 4 of the buckle, which is usually made of metal and has more or less sharp edges and corners, is protected by the leather or fabric cover or shield 5, so that said metal member will not engage the lining of the vest or other clothing of the wearer and is thereby 65 prevented from wearing or tearing the same, and the tab 5^a, which extends freely beyond the member or lever 4, can be readily grasped by the user for swinging back the lever for opening or closing the buckle, as the tab end 70 portion 5^a extends free and flexibly beyond the stitching 6.

Having now described my invention, what I claim is—

1. A suspender-buckle comprising a supporting-frame and a gripping member movably connected therewith and provided with a flexible cover substantially entirely inclosing said member to prevent contact of the member with a garment and having a flexible tab-like portion extending beyond said member, substantially as described. 80

2. A suspender-buckle comprising a supporting-frame and a gripping member pivotally connected therewith and provided with a leather cover folded substantially around said member and having its opposed portions secured together to prevent contact of the member with a garment, said cover being provided with a flexible extended tab-like portion extending beyond the member, substantially as described. 90

3. A suspender-buckle comprising a supporting-frame and a lever pivotally connected therewith and provided with a tooth and hav- 100

ing a flexible cover folded substantially entirely around said lever and provided with an aperture through which said tooth projects, the opposed members of said cover being secured together and a tab-like portion projecting beyond the lever from said cover, substantially as described.

4. A suspender-buckle comprising a frame, a lever pivotally connected therewith and provided with a tooth and an extended part, and a flexible cover folded substantially entirely around said member inclosing said extended part, the opposed portions of said cover being secured together, a tab-like portion of said

cover extending freely beyond said lever, substantially as described.

5. A suspender-buckle comprising a supporting-frame, a lever pivotally connected therewith, and a cover folded substantially entirely around said lever, the opposite webs of the cover being secured together, said cover having a flexible integral tab-like portion extending freely beyond the lever, substantially as described.

HENRY J. GAISMAN.
